UNITED STATES PATENT OFFICE.

MARK KOSICH, OF WASHINGTON, DISTRICT OF COLUMBIA.

PERMUTATION-LOCK.

1,310,704.

Specification of Letters Patent. Patented July 22, 1919.

Application filed January 13, 1919. Serial No. 270,895.

To all whom it may concern:

Be it known that I, MARK KOSICH, a subject of the Government of Montenegro, residing at Washington, in the District of Columbia, have invented certain new and useful Improvements in Permutation-Locks; and I do declare the following to be a full, clear, and exact description of the invention, such as will enable others skilled in the art 10 to which it appertains to make and use the same.

My invention has for its principal object to provide a comparatively simple and inexpensive permutation or combination lock 15 which will be particularly well adapted for use upon safes and vaults, although it is, of course, also applicable for other purposes.

A further object is to provide a lock in which a sliding handle is provided for operating the bolt or bolts, and in which the locking of such bolt or bolts is accomplished by locking of said handle through the instrumentality of permutation means housed therein.

With the foregoing in view, the invention resides in the novel features of construction and novel association of parts to be herein-after fully described and claimed, reference being made to the accompanying drawing 30 which forms a part of this application.

Figure 1 is an elevation of a door equipped with the invention.

Fig. 2 is a horizontal section of the lock with parts in elevation, showing the relation of parts when the bolts are extended.

Fig. 3 is approximately a duplicate of Fig. 2 but discloses the relation of parts when the bolts are retracted.

Fig. 4 is a vertical section on the plane of 40 the line 4—4 of Fig. 3.

Fig. 5 is an elevation of the permutation lock means, the handle being broken away and in section to illustrate such means.

Fig. 6 is a transverse section on the plane 45 designated by the line 6—6 of Fig. 4.

Fig. 7 is an end elevation of one of the tumblers.

Fig. 8 is a detail section on the plane of 50 the line 8—8 of Fig. 7.

Fig. 9 is a perspective view of one of the indicating rings with which the tumblers are equipped for properly positioning them to release the lock.

Briefly speaking, the lock consists of a 55 hollow sliding handle H mounted on a door D or other suitable support, one or more

bolts B carried by the door, connecting means C between the handle and bolts for operating the latter from the former, lock means L for holding the handle against shifting, and adjusting means A whereby the combination may be varied as required.

The door or the like D is here shown as provided with four of the bolts B and the inner side of said door is formed with channels 1 in which said bolts are mounted, a plate 2 being secured over said channels by screws or the like 3. The several channels 1 open at their inner ends into a recess 4 formed in the door D, said recess leading to 70 the exterior of said door and being by preference of greater diameter at its inner end than at its outer end. The handle H extends at its inner end into the recess 4 and the connecting means C between said handle 75 and the bolts B, are located in said recess, said connecting means being herein shown in the form of one piece links extending diagonally from the handle to the bolts, in such manner as to project said bolts when 80 the handle is forced inwardly and to retract them when an outward pull is exerted on said handle.

For supporting the handle H, a post 5 is fixedly mounted on the door D and extends 85 outwardly from the recess 4, the inner end of said post being equipped with a cylindrical head 6 which is rotatable in an opening 7 in the door, this rotary mounting being provided in order that the post 5 may be 90 turned to change the combination of the lock in a manner to be described. To normally hold the post 5 against rotation, a pivoted arm 8 and a toothed ring 9 are provided. The arm 8 is pivoted at 10 to a plate 11 secured on the inner end of the post 5, while the toothed ring 9 surrounds the inner end of the post and is secured by screws or the like 12 to the inner side of the door. The arm 8 is adapted to engage any of the teeth 95 of the ring 9 and it will thus be seen that different rotary adjustments of the post 5 may be made. To retain the arm 8 in engagement with the ring 9, a keeper 13 is provided, said keeper being shown in the 100 form of a dished plate receiving the ring 9, the arm 8, and the plate 11, screws or the like 14 being employed for detachably securing said keeper to the door so that it may be removed whenever required to 110 change the combination of the lock.

The handle H is formed of an inner sec-

tion 15 and an outer section 16 which is hollow throughout the greater part of its length. The section 15 is provided with a bore 17 through which the post 5 extends 5 and the outer end of said section 15 is removably received in the inner end of the hollow outer section 16, a screw or the like 18 being provided for connecting the two sections. When the handle is forced in- 10 wardly to project the bolts, the screw 18 is inaccessible, but when the handle is withdrawn as in Fig. 4, the screw in question may be removed to permit disassembling of the lock.

15 As one means of connecting the links C to the handle H, a collar 19 has been shown surrounding the inner handle section 15 and clamped between a shoulder 20 on said section and the inner end of the outer sec- 20 tion 16. It will be understood that other means could be provided for connecting the inner ends of the links C to the handle H.

The post 5 extends through the hollow portion of the outer handle section 16 and 25 is provided on its outer end with a removable head 21 sliding in the bore 22 in the solid outer end or knob 23 of said handle section, the portion of the post in the hollow part of the handle being provided with 30 spaced lateral projections 24 suitably located.

Rotary tumblers 25 are mounted in the hollow handle section 16 and are by preference carried within a sleeve 26 which is se- 35 cured by a screw or the like 27 to the outer end of the handle section 15, said sleeve having internal rings 28 which space the tumblers apart and hold them against shifting longitudinally of the handle. Each 40 tumbler is provided with an opening through which the post 5 passes and with a groove 29 which may travel over the adjacent projection 24, when the several grooves are alined with their respective pro- 45 jections, thus permitting the handle H to move outwardly and retract the bolts B. When the handle is forced inwardly and the tumblers 25 rotated to move the grooves and projections out of alinement, the handle 50 is locked against movement on the post 5 and consequently the lock cannot be released.

To render the tumblers 25 accessible for operation, one side of the sleeve 26 is cut- 55 away as shown at 30, this cut-away portion registering with a similar slot 31 in the handle section 16, and if desired, an ap- 60 tered plate 32 may be secured over the slot 31 as seen in Figs. 4 and 6, the openings of said plate and the slot in question being of sufficient size to allow the fore-finger to be inserted for the purpose of turning the tumblers.

In order that the tumblers may be prop- 65 erly positioned, indicating rings 33 are

mounted thereon, and these rings are pro- 70 vided with projections 34, receivable in any one of a number of sockets 35 with which the tumblers are provided. When the lock is disassembled, one or more of the pro- 75 jections 34 may be withdrawn from its socket and disposed in another and by this means, it will be seen that a different character must appear at the opening of the plate 32, in order to properly set the tum- 75 blers for releasing the lock.

From the foregoing, taken in connection with the accompanying drawings, it will be seen that I have provided a permutation lock of rather simple and inexpensive 80 nature, yet one which will be highly ef- ficient and in every way desirable, the de- vice being particularly well adapted for use upon safes and vaults. Since probably the best results are obtained from the details 85 disclosed, they may well be followed, but within the scope of the invention as claimed, considerable latitude is allowed for making numerous changes in minor details. Fur- 90 thermore, it is to be understood that the lock is applicable for numerous purposes and is not, therefore, restricted to use upon safes and the like.

What I claim is:

1. The combination with a closure and a 95 bolt carried thereby; of a hollow handle ex- tending from said closure and bodily slid- 100 able inwardly and outwardly, means actu- ated by the sliding action of said hollow handle for operating said bolt, and means in said handle for locking the latter against sliding.

2. The combination with a closure and a bolt carried thereby; of a hollow handle 105 extending from said closure and bodily slid- 110 able inwardly and outwardly, means actu- ated by the sliding action of said hollow handle for operating said bolt, and permu- tation means in said handle for locking the latter against sliding.

3. The combination with a closure and a bolt carried thereby, said closure having a 115 recess; of a post fixedly mounted on said clo- 120 sure and extending outwardly from said re- cess, a hollow handle mounted on said post for longitudinal sliding thereon and extend- 125 ing into said recess, means actuated by the sliding action of said hollow handle, for oper- ating said bolt, and a plurality of tumblers mounted in and movable bodily with said hollow handle, said tumblers and post hav- 130 ing coacting means for locking said handle against sliding.

4. The combination with a closure and a bolt mounted thereon, said closure having a 125 recess, a post fixedly mounted on said clo- 130 sure and extending outwardly through said recess, a handle mounted on said post for longitudinal sliding thereon and extending into said recess, said handle being formed

- of inner and outer sections, the outer section being hollow and the inner section extending into said outer section, means detachably uniting said handle sections for 5 sliding in unison on said post, means for operating said bolt upon sliding of said handle, and permutation means in said outer handle section for locking it to said post to normally prevent such sliding.
- 10 5. The combination with a closure and a bolt mounted thereon, said closure having a recess, a post fixedly mounted on said closure and extending outwardly through said recess, a handle mounted slidably on said post 15 and extending into said recess, said handle being formed of inner and outer sections, the outer section being hollow and the inner section extending into said outer section, means detachably uniting said handle sections, means for operating said bolt upon 20 sliding of said handle, a sleeve secured to said inner handle section and extending into said outer handle section, said outer handle section and sleeve having alined slots and 25 said sleeve having internal circumferential
- spacing rings, and rotary tumblers mounted in said sleeve between said spacing rings, said tumblers and said post having coacting means for locking the handle against sliding on said post. 30
6. The combination with a closure, a bolt operating handle therefor, a post upon which said handle is mounted, permutation means for locking the handle to the post, including projections on the latter, said post 35 being rotatably mounted to allow disposition of said projections at different locations to change the combination of the lock, a toothed ring surrounding the inner end of said post and secured to the closure, a piv- 40 oted arm carried by said post for coaction with the teeth of said toothed ring to hold said post after rotation thereof, and a keeper removably secured to the closure and preventing disengagement of said pivoted 45 arm and teeth until removed.

In testimony whereof I have hereunto set my hand.

MARK KOSICH.
